TRANSVERSE FRAME FOR RIGID AIRSHIPS

Application filed October 23, 1924, Serial No. 745,464, and in Great Britain October 30, 1923.

As at present constructed the main transverse frames of rigid airships consist of a series of girders arranged in the form of a polygon and cross braced with a large number of wires. Owing to the forces which are imposed on these transverse wires when there is a difference of pressure between two adjacent gasbags, very considerable stresses are imposed by the wires on the girders of the transverse frame. If the wires are initially stressed (as is inevitable) before any gasbag pressure comes on to them, the ultimate tension set up in the wires by the gasbag pressure is very considerable, and hence it would be of great advantage if a certain amount of initial slackness could be allowed in these wires, which would then cease to act as cross braces and would merely serve to prevent rapid surging movements of the gas in the airship and also to prevent large pressures on the nose or tail when the airship becomes inclined.

According to the present invention the transverse frame is so constructed that it is not obliged to rely on the transverse wiring to resist distortion under the forces which are normally applied to it but such frame is self-supporting, and consequently such transverse wiring could initially be slack with the advantages above described.

For this purpose the transverse frames or some of them are in the form of a continuous trussed structure preferably of triangular or prismatic cross section, and if the point of minimum bending moment is at the highest point of the frame, this structure may be of decreasing rigidity or cross section from the lowest point in either direction towards the top of the frame.

For example, in the construction of transverse frame illustrated in side and end elevation respectively in Figs. 1 and 2 of the accompanying drawings, the bottom half of the frame is built up to form a stiff crescent-shaped cradle of triangular cross section of a depth and width decreasing from a maximum at the bottom in either direction towards the top. The frame may be regarded as composed of a continuous series of units of triangular or wedge form, the base members A of

which are spaced a considerable distance apart at the bottom of the frame at which point the side members B have maximum length. The angular points of successive pairs of side members are connected by a ridge member C, and the several members may be cross-braced as by tensioned diagonal wires D or by diagonal struts E. With such a structure for the lower half of the frame, the top half may be quite light and may consist as shown in Fig. 1 simply of a series of simple rods connected in a semi-circle, the action of the gas pressure tending to maintain the normal configuration of this part of the frame.

The provision of a strong cradle such as the bottom half of the truss frame above described has the additional incidental advantage of being suitable for carrying static loads, such as fuel, water ballast etc. which can be more economically carried in this manner than if they were distributed along a longitudinal keel, which latter is eliminated by the construction of transverse frame according to this invention. Further, the frames can be used as gas-trunks and also as passages for the use of the crew.

In the modified construction of Figs. 3 and 4, the limbs of the crescent-shaped trussed structure extend to the top of the frames and taper continuously in either direction from the lowest towards the highest point thereof, but otherwise the construction of the frame is identical with that of Figs. 1 and 2.

In either of these constructions the depth of the frame may be varied as shown, while the width of the same remains constant.

Alternatively the frame may be of uniform depth and width and concentric with the outer periphery instead of eccentric as in Figs. 1-4, if a distribution of loads is used which makes this desirable or if simplicity of construction is achieved thereby.

Such a frame is shown in Figs. 5 and 6, in which the same reference characters are applied to the several members of the structure as are used with respect to the corresponding members in Figs. 1-4, and both the width and depth are constant. As a further alternative, the width of the frame structure may be

varied around the periphery, while the depth remains constant.

In the drawings, the invention has been represented as applied to rigid airships in which the transverse frames are held in position by peripheral rigid longitudinal members.

It has been proposed, in rigid airships having main wheel-like transverse frames connected by peripheral longitudinal wires and braced by tensioned radial spokes attached to a central boom, to use additional radial wires without tension and in conical arrangement to take the pressure of the gas bags. It has also been proposed, in such rigid airships and in rigid airships having main wheel-like transverse frames connected by peripheral rigid longitudinal members and braced by tensioned radial spokes, to use rims formed of triangular or prismatic cross section. But the arrangements just referred to are not adapted to resist distortion in use without the tensioned wire spokes and therefore are not included in the present invention.

Slack wires H may extend across the space enclosed within the periphery of the transverse frame and be connected with said frame to prevent rapid surging movements of the gas in the gas bags between said wires and to prevent large pressures of gas on the nose and tail of the airship when the airship is in inclined position.

Having thus described the nature of said invention and the best means we know of carrying the same into practical effect, we claim:

1. A rigid airship frame comprising a plurality of transverse frames connected to one another by rigid peripheral longitudinal members, each of said transverse frames comprising a trussed structure of prismatic cross section and of decreasing rigidity from the lowest point of the frame towards the top thereof.

2. A rigid airship frame comprising a plurality of transverse frames connected to one another by rigid peripheral longitudinal members, each of said transverse frames comprising a trussed structure of prismatic cross section and of decreasing width in either direction from the lowest point of the frame towards the top thereof.

3. A rigid airship frame comprising a plurality of transverse frames connected to one another by rigid peripheral longitudinal members, each of said transverse frames comprising a trussed structure of prismatic cross section and of decreasing depth in either direction from the lowest point of the frame towards the top thereof.

4. A rigid airship frame comprising a plurality of transverse frames connected to one another by rigid peripheral longitudinal members, each of said transverse frames com-

prising a trussed structure of prismatic cross section and of decreasing width and depth in either direction from the lowest point of the frame towards the top thereof.

In testimony whereof we have signed our names to this specification.

VINCENT CRANE RICHMOND.
GEORGE HERBERT SCOTT.
